SEWING MACHINE

Howland F. Briggs, Buffalo, N. Y., assignor to
 Consolidated Packaging Machinery Corpora-
 tion, a corporation of New York

Application September 19, 1933, Serial No. 690,053

10 Claims. (Cl. 112—200)

My invention relates to sewing machines and more particularly to sewing machines adapted for sewing heavy materials.

In sewing the mouths of paper bags intended to contain large quantities, for example 100 pounds, of materials such as cement or the like, it is necessary to provide a sewing machine which is not only capable of sewing through a considerable number of thicknesses of heavy kraft paper, for example twenty or more, but is capable of accomplishing this very rapidly and of producing a tightly stitched seam.

It has been found that when it was attempted to employ sewing machines which had proven to be satisfactory for the sewing of cloth bags or the like, for the sewing of multi-ply paper bags made of heavy kraft paper, such sewing machines proved unsatisfactory for several reasons. Aside from the fact that these machines were insufficiently strong to perform the actual work, a solution of the problem necessitated more radical re-design than could be effected by mere strengthening of the several parts thereof. It was found, for example, that such sewing machines could not be adjusted to give sufficiently tightly stitched seams without creating a tendency to tear the paper being sewn or to break the stitching thread.

Moreover, it was also found that, whereas in previous sewing machines which operated satisfactorily on cloth bags, slight inaccuracies of movement of the feeding mechanism and the stitch-forming mechanism did not produce serious difficulties in sewing cloth, by reason of the more or less flexible or sleazy character of cloth as compared with paper, when such machines were employed for the stitching of heavy paper bags or the like, such irregularity of movement tended to form irregular and defective stitching, as the relatively stiff and rigid paper did not accommodate itself to any irregularity of movement.

In the co-pending applications of Howland F. Briggs and Robert N. Cundall, Ser. No. 689,400, filed September 14, 1933, and of Lincoln A. Cundall and Robert N. Cundall, Ser. No. 690,988 filed September 26, 1933, there are described and claimed certain improvements in sewing machines and sewing machine mechanisms, which are of improved utility with respect to sewing heavy and more or less rigid materials, such as the mouths of multi-ply bags formed from heavy paper or the like.

An object of my present invention is to provide further improvements in the design and op-

eration of sewing machines and sewing machine mechanism, whereby still more improved results may be secured, especially with respect to the sewing of heavy and rigid materials such as paper.

A second object of my invention is to provide a sewing machine having improved stitch-forming mechanism.

A further object of my invention is to provide improved means for regulating the tension of the thread from which the stitching is formed, whereby paper or similar material may be provided with a firm and tight stitching without, however, placing too severe a stress upon the thread or causing the thread or stitching to damage or cut the material being sewn.

My invention has for further objects such additional improvements in operative advantages and results as may hereinafter be found to obtain.

My invention is especially, although not necessarily, adapted to be employed in connection with a sewing machine having a feeding mechanism such, for example, as that described and claimed in the aforesaid application of Lincoln A. Cundall and Robert N. Cundall, and having a needle adapted to reciprocate along an axis parallel to the axis of the main drive shaft of the sewing machine. In one aspect, my invention contemplates the provision of an improved looper mechanism adapted to cooperate with the aforesaid needle to form a stitch such, for example, as a so-called "double-thread chain stitch", which mechanism is so designed as to impart an improved motion characteristic to the looper itself, thereby facilitating the formation of the stitch and rendering the stitching more accurate and better adapted to the stitching of more or less stiff or rigid material such as heavy paper.

In another aspect, my invention comprises means for feeding thread to the aforesaid needle as required for the formation of the stitching, whereby the tension of the thread, as it is fed to the stitch-forming mechanism, is periodically varied in accordance with the movements of the stitch-forming mechanism, in such manner that paper or other stiff and rigid material may be tightly stitched without injuring the material. More specifically, the thread-tensioning mechanism of my present invention contemplates the provision of a device for applying a normal tension, such as might be suitable for sewing cloth, to the needle thread during the entire sewing cycle, together with a second device for superimposing a heavier tension upon the needle thread during a portion of the cycle, the inter-

mittent functioning of the second device being governed in accordance with the cycle of the needle, the looper and the feed mechanism.

In order that my invention may be clearly set forth and understood, I now describe, with reference to the drawings accompanying and forming a part of this specification, an improved form and manner in which my invention may be embodied and utilized. In these drawings,

10 Fig. 1 is an elevational view of a sewing machine constructed in accordance with my present invention, the usual protective cover of the machine being removed in order to illustrate the moving parts of the machine more clearly;

15 Fig. 2 is an end-elevational view of a portion of the apparatus illustrated in Fig. 1;

Figs. 3 and 4 are vertical sectional views of the apparatus illustrated in Fig. 1, taken along the lines 3—3 and 4—4 of Fig. 1, respectively;

20 Fig. 5 is a horizontal-sectional view of a portion of the apparatus illustrated in Figs. 1, 3 and 4, taken along the line 5—5 of Fig. 1;

Figs. 6, 7 and 8 are plan, side-elevational and end-elevational views, respectively, illustrating 25 more or less diagrammatically the relative positions of the needle, the looper and the material being sewed, at such time as the needle has been withdrawn from the material being sewed and is about to approach the same to form another 30 stitch;

Figs. 9, 10 and 11; 12, 13 and 14; 15, 16 and 17; 18, 19 and 20; and 21, 22 and 23, are similar views, respectively, illustrating the relative positions of the needle, the looper and the material being sewed, during subsequent portions of the stitching cycle, and illustrating the manner in which the stitch is formed;

Figs. 24 and 25 are enlarged sectional and side-elevational views, respectively, illustrating the 40 appearance of the chain stitch formed by the movements of the needle and looper illustrated in Figs. 6 to 23 inclusive;

Fig. 26 is a horizontal sectional view of a portion of the apparatus illustrated in Fig. 1 taken 45 on the line 26—26 of Fig. 1; and

Figs. 27 to 31 inclusive are diagrammatic motion studies of parts of the sewing machine from which a clear concept of the improved stitch forming mechanism may be obtained.

50 Similar reference numerals indicate similar parts in each of the several views of the drawings. It will be understood that while I have for convenience referred to the various figures as being in plan or elevation or in vertical or horizontal section, my improved sewing machine is adapted to be used in any position.

Referring now to the drawings, the sewing machine has a frame member or assembly 1 having the usual opening or throat 2 to permit the passage of material therethrough. A main drive shaft 3 is suitably journaled in bearings 4 and is provided with pulleys 5 and a hand wheel or fly wheel 6. The shaft 3 is preferably, but not necessarily, located with its principal axis normal to the plane of the material being sewn, which passes between a feed plate and an adjustable presser foot 8 mounted upon the usual presser foot rod 9.

The feeding of the material to be stitched through the machine is accomplished by means of 70 a feed mechanism comprising in part a feed dog 11 which, in the present instance, is constructed and driven in the manner set forth and claimed in the aforesaid co-pending application of Lincoln A. Cundall and Robert N. Cundall. It will, however, be understood that while this is the preferred

feed mechanism, other suitable feed mechanisms may be employed when so desired.

As set forth in the co-pending application of Lincoln A. Cundall and Robert N. Cundall, the feed dog 11 is attached to one end of an arm 12 which is mounted at its opposite end upon a pin 13 extending parallel to the direction of movement of the material being sewn, in such manner as to be capable of motion both along and about the principal axis of the pin 13. The sliding motion of the member 12 along the pin 13 is derived from an eccentric device 14 mounted upon the shaft 3, which is connected by means of a pitman 15 to one end of a crank member 16 pivotally mounted upon a pin 17 journaled in a lug 18 which is attached to the frame 1. The end of the crank member 16 not connected to the pitman 15 is provided with a slotted portion 19 through which passes a pin-member 21 biased by a spring 22. As the shaft 3 revolves, the eccentric 14 causes the crank member 16 to oscillate, thus reciprocally sliding the member 12 to and fro along the pin 13, and providing the feed dog 11 with a component of motion in the direction of movement of the material to be sewn as well as a component of motion in the opposite direction.

In order to cause the material being sewn to advance in a series of intermittent forward movements it is necessary for the feed dog 11 to be periodically retracted and advanced through 30 openings 23 in the feed plate 7, the motion being such that the forward motion of the feed dog 11 takes place when the feed dog is advanced through the openings 23 to engage the material against the yielding support of the presser foot 8. At the 35 end of each forward stroke, the feed dog 11 must be retracted through the openings 23 out of engagement with the material being sewn, in which position it moves backward out of contact with the material being sewn in order to prepare for 40 another forward stroke.

The advancement and retraction of the feed dog 11 through the feed plate 7 is accomplished by rocking the member 12 about the principal axis of the pin 13, and this is effected by means of an 45 eccentric device 30 mounted on the shaft 3. The eccentric device 30 is connected by means of a pitman 31 to a block 32 adapted to reciprocate along a fixed straight path defined by a slot 33 formed by one or more members 34 attached to 50 the frame 1. The block 32 is pivotally connected by means of a rigid "dumb-bell" link 35, having spherical heads at either end thereof, to the member 12 at a point considerably removed from the pin 13. The spherical ends of the link 35 are 55 suitably journaled in recesses formed in the block 32 and the member 12, respectively.

It will thus be apparent that when the block 32 is reciprocated up and down as viewed in Figs. 1 and 4, the member 12 is reciprocally 60 rocked about the pin 13. The combined effect of the reciprocal movements of the ends of the link 35 gives the feed dog 11 a closed-path motion, which path may be varied to a considerable extent by varying the relative positions and 65 lengths of stroke of the members 12 and 32. In any event, however, the feed dog 11 is caused periodically to advance through the feed plate 7 to engage the material being sewn against the presser foot 8, then to advance the material 70 being sewn by a distance equal to the distance between successive stitches, then to be withdrawn or retracted through the feed plate 7 out of engagement with the material being sewn and finally to return to its initial position ready to be 75

advanced through the feed plate 7 for another forward stroke. The material being sewn is thus caused to advance between the feed plate 7 and the presser foot 8 in a series of short intermittent forward motions.

The stitch-forming mechanism comprises in part a needle 40 mounted upon one end of a needle bar 41 slidably journaled in bearings 42 and 43, and having a principal axis normal to the plane of the material being sewn. The needle bar 41 is reciprocated along its axis by means of an eccentric device 44 comprising an eccentric cam, having a rounded face, mounted upon the main drive shaft 3 and which, through a pitman 45, a bell crank 46 pivotally mounted at 47, a link 48 and a block 49, drives the needle bar 41. The timing of the reciprocating motion of the needle bar 41 is such that the needle 40 enters the material being sewn just after each forward motion of the latter effected by the feed dog 11, penetrates through the material for a sufficient distance to cooperate with other stitch-forming mechanism to be described hereinbelow to form the beginning of a new stitch, and is then withdrawn from the material being sewn just prior to the time at which the feed dog 11 again engages the material being sewn in order to advance into position for the next stitch. During the period of advancement of material being sewn, the needle 40 travels away from the material to the position illustrated in Fig. 1 and then returns, entering the material just after the forward stroke of the feed dog 11 has been completed.

In order to form a double-thread chain stitch, one thread is supplied to the material by means of the needle 40 while another thread is supplied to the opposite side of the material by means of a looper 51, which cooperates with the needle 40 to cause an interweaving of the two threads on one side of the material being sewn, thus producing an interlocked stitch. In order to cause interlocking of the two threads, the looper 51 is caused to travel in a closed path (which lies in an imaginary cylindrical surface generated about the pin 56 as an axis) drawn about an imaginary line comprising the principal axis of the needle 40 and needle bar 41. In previous sewing machines having loopers for the purpose indicated, the motion of this closed path of the looper has ordinarily had the shape of a rather flat ellipse, but, according to my present invention, I provide improved mechanism whereby the path of the looper 51 may be made more or less oval in configuration in order to improve the accuracy and refinement of the manner in which the stitch is formed, and I now describe the mechanism whereby this result is obtained.

The looper 51 is held in a bifurcated clamp 52 having a suitable fastener 53. The opposite end of the clamp 52 is rigidly fixed by means of a set screw 54 or other fastening means to a member 55 which is mounted upon a pin 56 extending parallel to the stitching line, that is to say, parallel to the direction of movement of material being sewn. The member 55 is movable both about and along the principal axis of the pin 56.

It will be noted from inspection of Fig. 1, that in order to maintain the effective portion of the looper 51 at a uniform distance from the material being sewn, the looper 51 is curved on a radius extending to the center of the pin 56. Since it is evident that the looper 51 thus pivots

about the pin 56, it follows that the path of any fixed part of the looper 51 must be equidistant at any point from the axis of pin 56. It will, however, be understood that when reference is made herein to the "substantially oval" path of the looper 51, that such oval path lies in an imaginary cylindrical surface, the radius of revolution of which depends upon the radial distance between the principal axis of the pin 56 and the looper 51.

In the preferred instance shown, the motions of the member 55 both along and about the principal axis of the pin 56 are effected by means of a single eccentric device 57 mounted upon and driven by the shaft 3. Attached to the eccentric device 57 is a pitman or connecting rod 58 which, at its lower end, passes through a sleeve member 59 pivotally mounted at one end upon a pin 60 secured to the frame 1. As will be apparent from Fig. 4, the rod 58 is free to move vertically with respect to the sleeve member 59 as the eccentric 57 rotates. However, as this occurs, the lateral movement of the rod 58, as viewed in Fig. 4, causes the sleeve member 59 to rock slightly about the pin 60.

The end of the sleeve member 59 opposite the pin 60 is pivotally attached by means of a pin 61 to a connecting link 62, the other end of which is eccentrically connected by means of a crank pin 63 to a member 64 adjustably mounted on one end of a short shaft 65 journaled in a bearing 66 fastened to the frame 1. The end of the shaft 65 opposite the member 64 is bent at 67 and terminates in a yoke 68 operatively connected to a collar 69 which is freely mounted on the pin 56 but is rigidly attached to the member 55.

Thus, as the shaft 3 rotates, the eccentric device 57, through the rod 58, causes the member 59 to oscillate slightly about the pin 60, and the effect of this oscillation of the member 59 operates through the member 62 and the crank pin 63 to oscillate the shaft 65 in the bearing 66, thus reciprocally moving the member 55 to and fro along the pin 56 but without exerting any influence on the angularity of the member 55 with respect to the axis of the pin 56.

For the purpose of providing an oscillatory movement of the member 55 about the principal axis of the pin 56, I provide a block 71 attached to the lower end of the rod 58. The block 71 is suitably recessed to receive one end of a so-called "dumb-bell" link 72, the opposite ends of which are spherical in shape. That end of the link 72 opposite the end pivotally secured to the block 71 is pivotally attached to the member 55, which is suitably recessed to receive the same.

It will be apparent from inspection of Fig. 1 that, as the eccentric device 57 causes the rod 58 and the block 71 to reciprocate in a substantially vertical line, this reciprocation of the block 71 will act through the link 72 to rock the member 55 about the pin 56, thus raising and lowering the looper 51 as viewed in Fig. 1. It will be noted that in Fig. 1 the eccentric device 57 is shown at the top of its stroke, the block 71 being correspondingly at the top of its stroke and that in this position the link 72 is only slightly out of a horizontal position as viewed in the drawings.

It will furthermore be apparent that as the block 71 moves downwardly it will have substantially no effect upon the member 55 until the link 72 is about as far below a horizontal position as it is shown above in Fig. 1, that is, on the opposite side of a horizontal plane passing through the

end of the link 72 which is attached to the member 55. In this latter position, the member 71 is not more than about half way down its path of travel. Consequently, during the first half of the downward stroke and the last half of the upward stroke of the member 71 there is relatively very little change in the angularity of the member 55 about the pin 56.

However, as the member 71 moves farther down toward the lower end of its stroke, the angularity of the link 72 with respect to the member 55 changes more rapidly and causes the member 55 to move more rapidly about the pin 56 in a clockwise direction as viewed in Fig. 1. Toward the end of the downward stroke of the member 71, the turning movement of the member 55 slows down gradually, then gradually accelerates in the opposite direction as the member 71 reciprocates and passes through the first half of its upward stroke.

It will thus be apparent that the looper 51 is raised quite rapidly during such time as the block 71 is moving downward from a position midway of its path to a position near the bottom of its path and, conversely, the looper 51 is rapidly lowered as the block 71 moves upward from a point near the bottom of its path to a point about midway of its path, while the movement of the looper 51 about the pin 56 is relatively very slow during the remainder of the path of travel of the block 71 both at the top and bottom of its stroke.

It will further be apparent from the above, as well as from inspection of the drawings, that, due to the integrating effect of the member 55 on the translated motions of the member 71 and the member 68, the looper 51 passes through a closed path lying in an imaginary surface generated about the center of the pin 56, which closed path encloses an imaginary line forming an extension of the principal axis of the needle 40 and the needle bar 41.

The timing and relative positioning of the various parts will be appreciated from an inspection of Figs. 27 to 31 inclusive. Fig. 27 represents the path of the needle tip along line A B, entering the material at about 38° rotation of the main shaft and leaving it at about 322°. Fig. 31 likewise is a study of the motion of the feed dog, the shaded portion indicating the operative part of the feed dog's travel when projected through the throat plate, the needle being at this time withdrawn. Fig. 28 represents the path of member 71, starting at D (0° rotation of the main shaft) and reaching E (180° rotation) at its lowest point. Fig. 29 represents the path of the yoke 68, extending from F (90° rotation) and reaching G (270° rotation). Fig. 30 represents the path of the eye of the looper in its relation to the needle which reciprocates normal to the plane of Fig. 30 at H. The lines D E and F G have been superimposed in correct relation to each other in dotted outline. It is to be noted that, due to the pivoting of arm 52 about pin 56, the looper is at its highest position at 180° at the instant that member 71 is at its lowest point at E.

The dumb-bell link 72 plays an important part in determining the path of the looper and operates as follows. It will be apparent that for forty degrees inclination more or less of the link 72 on each side of point D, the block 71 will have little or no effect on the looper. This is due to the fact that the dumb-bell link is of such a length and so positioned that it passes through

a horizontal plane at 20°, and for 20° on either side of this horizontal plane will neither push nor pull to any extent on member 55. After passing 40°, however, the link rapidly tends to assume a vertical position and pulls down the back of member 55 to raise the looper until member 71 reaches E at 180°. The return movement of the looper is identical but in reversed order, commencing at 180°, traveling rapidly to about 320°, and remaining stationary through 360°.

During this time the yoke 68 traverses its path F G reaching its extreme positions at 90° and 270°. As both the dumb-bell link 72 and yoke 68 act upon the looper the result will be to give it a motion along a closed path about the needle. This path is, from 90° to 270°, the resultant of two forces traveling in straight lines at right angles with simple harmonic acceleration, and hence is a flat ellipse. However, from 320° to 40° there is no vertical component so that portion of the path is a straight horizontal line.

The sequence is such that the looper, starting at 0°, or for clarity, starting at 320°, moves quickly horizontally to 40°, moves quickly upward to 180° and then quickly downward to 320°. This path may be defined as oval-shaped, or more accurately as an oval with a flattened end. The advantages arising from this will be more apparent hereafter.

The manner in which the looper cooperates with the needle to form a chain stitch may best be understood with reference to Figs. 1 and 6 to 23, inclusive, in which the relative positions of the needle, the looper and the material being sewed are illustrated at a number of points in the stitch-forming cycle.

In Figs. 1, 6, 7 and 8, the needle 40 and looper 51 are illustrated at what may be called for purposes of explanation the beginning of the stitching cycle and which, for purposes of reference may be designated as 0° of rotation of the shaft 3. The material being sewn is designated by the reference numeral 75 and at this point is being moved forward in the direction indicated by the arrow by means of the feed dog 11. The needle 40 is at this time well withdrawn from the material 75 and is about to move in the direction of the arrow, that is to say, toward the material being stitched, while the looper 51 is moving across the stitching line in the direction opposite to the direction of movement of the material being sewn. It will be noted that the needle thread 76 passes from the needle through the last stitch in the material 75, around the looper 51 and back to the material being stitched, while the looper thread 77 extends downward through the loop thereby formed in the needle thread 76 to the bottom of the looper and thence to the material being stitched.

In Figs. 9, 10 and 11, the needle 40, looper 51 and material 75 are shown in positions which follow the positions illustrated in Figs. 6, 7 and 8, by about 80° of rotation of the shaft 3. The material 75 has now been moved forward by exactly the distance between successive stitches and is no longer engaged by the feed dog 11 but is stationary while the needle 40 has just pierced the material 75 for the next stitch. The looper 51 has now moved to a point lying to the rear of the needle 40 and is moving upward, and, as illustrated in Fig. 11, the movement of the looper 51 has formed a "thread triangle", two sides of which are formed by the looper thread 77 while the remaining side of the triangle is formed by

the looped portion of the needle thread 76 which extends from the previous stitch around the looper 51 and is held in position by points or slight elevations in the face of the looper. It will further be evident from inspection of Figs. 9, 10 and 11 that the needle 40 is at this time about to enter the aforesaid triangle formed by the needle thread 76 and the looper thread 77.

Figs. 12, 13 and 14 illustrate the positions of the needle 40; the looper 51 and the material 75 at a position which corresponds to about 100° of rotation of the shaft 3 past the position illustrated in Figs. 1, 6, 7 and 8. The point of the needle 40 has now traversed the triangle formed by the looped needle thread 76 and the looper thread 77. The looper 51 is still rising and is about to rise to such position that the lower end of the looper 51 rises above the level of the needle 40 and it will therefore be apparent that the looper 51 is about to strip itself of the looped portion of the needle thread 76, the points on the looper being no longer able to hold the thread.

In Figs. 15, 16 and 17, the various parts are illustrated in a position corresponding to about 180° of rotation of the shaft 3 subsequent to the position illustrated in Figs. 1, 6, 7 and 8. At this time the needle 40 is near the point of maximum insertion through the material 75 and the looper 51 has now reached a point above the needle 40, thus stripping off that portion of the needle thread 76 which has heretofore been looped around the looper 51. At this time, the looper 51 is moving forward, that is to say, in the general direction of movement of material being sewed, over and across the needle 40, that is to say, to the side opposite the side on which the looper 51 is shown in Figs. 9 to 14, inclusive.

Figs. 18, 19 and 20, represent a position about 50° of rotation of the shaft 3 past the position illustrated in Figs. 15, 16 and 17, or a total of about 230° of rotation subsequent to the initial position illustrated in Figs. 1, 6, 7 and 8, and the needle 40 is now being retracted rapidly through the material 75. It will be evident from inspection of Fig. 18 that that portion of the needle thread 76 which has just been carried through the material 75 by the needle 40 is about to form a new loop on the forward side of the needle 40. The now descending looper 51, having released the previous loop, is about to enter the newly formed loop in the needle thread 76. The needle is preferably provided with a slight indentation which the point of the looper may enter for this purpose.

In Figs. 21, 22 and 23, the needle 40, material 75, and looper 51 are illustrated in the positions in which they are found after about 300° of rotation of the shaft 3 past the positions illustrated in Figs. 1, 6, 7 and 8. At this time, the point of the needle 40 is just about to be retracted from the material being sewed and the looper 51 has now descended through nearly all of its downward path. It will be further apparent that in thus descending, the looper 51 has passed through the looper portion of the needle thread 76 and will retain this looped portion of the needle thread 76 until its next subsequent upward stroke when the needle after piercing the material at the next stitching point will strip off this loop. It is also apparent that at this point the area of the thread triangle will begin to form and will be enlarging until the looper moves horizontally along the flattened lower end of its oval path. This triangle will be held at a maxi-

mum area during the time the looper passes from 320° through the position of Figs. 6, 7 and 8 to the position of Figs. 9, 10 and 11. There is thus formed a substantially large triangle which is retained for a long portion of a cycle and presents a large area for the needle to enter. This is of great advantage in that different timings of needle, looper or feed dog may be utilized to form variously altered stitches. It is also of great importance due to the relatively small character of the work being performed as it allows slipping or vibrations to slightly alter the relative positions of parts without allowing the stitch forming parts to fall or drop a stitch.

In Figs. 21, 22 and 23, the feed dog 11 is just engaging the material 75 and is about to move forward in the direction indicated by the arrow a distance equal to the distance between successive stitches. A feature of my improved structure is that due to the curved shape of the looper 51 and its operation in a generated surface, a more positive feeding device may be utilized. Thus while I have illustrated a feed dog having two short legs and one long leg, I may employ a feed dog having both its upper and lower legs of greater length than the middle leg. This will give a greater gripping surface and hence decrease the chances of the material slipping.

It will therefore be apparent to those skilled in the art, from inspection of the foregoing Figs. 6 to 23, inclusive, that the substantially flattened oval path of the looper 51, comprising as it does, alternate substantially vertical and substantially horizontal motions in a closed path, and enclosing an imaginary line forming an extension of 35 the principal axis of the needle 40, makes it possible, especially in combination with other features of my invention to be described hereinbelow, to produce a double thread chain stitch such as is more or less diagrammatically illustrated in Figs. 24 and 25 with the degree of precision and rigidity which is required in sewing relatively stiff materials such as heavy paper, and more especially in stitching the mouths of multi-ply kraft paper bags.

As has been stated hereinabove, in attempting to stitch heavy paper bags or other relatively stiff material, as distinguished from soft material such as cloth, it has been found difficult to obtain a tight stitching without putting sufficient tension on the thread to injure the material being sewn. This is due to the fact that prior devices have provided for substantially uniform thread tension during the entire stitch-forming period. When sewing light material such as cloth, the needle thread may be held under sufficient tension to give a considerable frictional drag on the thread as it is paid out in sewing. However, when sewing stiff, heavy materials, the needle thread is liable to break when the feed dog 11 pushes the material forward relative to the sewing machine against this heavy drag on the needle thread. This is particularly harmful and dangerous, especially when sewing such materials as paper which are fed through the machine in a series of intermittent jerking motions, and the material itself does not give readily but tends either to be torn by the thread or to break the thread depending upon the relative strength of the material and the thread.

According to my present invention, means are provided whereby any paying out of the needle thread may be resisted by a light tension during such portion of the stitch-forming period in 75

which the feed mechanism is advancing the material relative to the sewing machine, and by a considerably greater tension during such time as the needle is penetrating the material being sewn, which is essential for successful sewing.

Referring now to the drawings, the needle thread 76 is fed from a thread stand (not shown) through a thread guide tube 101 and through an adjustable thread-tension device 102 of conventional design. The thread 76 then passes between a pair of opposed discs 110 and 111 and thence through a thread tube 112 to an eye 113 mounted upon the left hand end of the needle bar 41, from which the thread 76 passes through eyes 114 to the needle 40.

The disc 111 is mounted upon one end of a leaf 115, and is urged toward the disc 110 by means of a spring 117 mounted upon an adjustable supporting member 118 preferably located about mid way of the leaf 115. A block 119 is provided for limiting the travel of the leaf 115.

The disc 110 is mounted upon a short sliding pin 121, suitably journaled in the frame member 1 and terminating in a rounded end 122 which bears against the face of a cam member 123 attached to one end of the shaft 3.

Thus, as the shaft 3 rotates, the cam 123 will act upon the end 122 of the pin 121 to urge the disc 110 against the flexibly biased disc 111, thus placing the thread 76 under the tension of the spring 117 during one portion of the period of the rotation of the shaft 3, that is to say, during a portion of the stitch-forming cycle, and during another portion of the cycle will relieve the disc 110 and the thread 76 from the pressure of the spring 117 exerted through the biased disc 111. The pressure exerted by the spring 117 is suitably adjusted in accordance with the character of the material being sewn and the tightness of the stitch desired.

The cam 123 is so designed that it causes the discs 110 and 111 to be pressed together at such time as the needle 40 is moving forward to penetrate the material being sewn, while relieving the additional tension upon the needle thread 76 during such time as the needle is being retracted out of the material being sewn and the feed dog 11 is advancing the material relative to the sewing machine. During this period in which the feed dog is moving the material being sewn, the material itself tends to drag the thread away from the needle and it would obviously cause too great a force to be applied to the thread were this force exerted by the feed mechanism to be allowed to oppose the relatively heavy tensional force which is necessarily applied to the needle thread during such time as the needle is penetrating the material being sewn.

In the preferred instance (diagrammatically illustrated in Fig. 27), the cam 123 is so designed that the needle thread 76 is maintained under the tension resulting from the compressive force of the spring 117 acting through the discs 110 and 111 over somewhat less than half of the total stitch forming period or, more specifically, over approximately 158° of rotation of the shaft 3. During the remaining 202° of rotation of the shaft 3 the paying out of the needle thread is resisted merely by the tensional force exerted by the device 102. In this instance the needle 40 enters the material being sewn at approximately 38° of rotation of the shaft 3 past the zero or starting position illustrated in Figs. 1, 6, 7 and 8, and the discs 110 and 111 grip the thread at

approximately 16° of rotation of the shaft 3 prior to the point at which the needle enters the material or, in other words, at 22° of rotation of the shaft 3 past the zero position illustrated in Figs. 1, 6, 7 and 8. At this point the feed dog 11 has reached its maximum forward feeding position and is about to travel away from the presser foot 8.

As the cycle proceeds, the cam 123 causes the discs 110 and 111 to be separated at 180° of rotation of the shaft 3 past the zero position, at which time the needle has reached its maximum forward position (to the right as viewed in Fig. 1) and the feed dog 11 is at its maximum rearward position and is about to move toward the presser foot 8 to grip the material and advance it forward. The feed dog 11 does not, however, engage the material being sewn and give it another forward movement until the needle 40 is withdrawn from the material. The portion of the needle stroke during which the thread is under tension from the discs is illustrated as part C of Fig. 27. The discs are held apart as the needle travels from 180° through 322° (when the needle leaves the material), through 0° (when the needle starts the next cycle), until 22° of the next cycle is reached.

It will be understood by those skilled in the art that the term "tension" as employed hereinabove is not intended to mean that the device 102 or the discs 110 and 111 exert a force tending to draw the needle thread back through the needle 40 at any time, but merely that the device 102 and the discs 110 and 111, when they are actuated to do so, exert a frictional drag upon the needle thread 76 which resists paying out of the thread to a greater or less extent depending upon whether only the device 102 acts upon the thread 76 or frictional force exerted by the device 102 is supplemented by the drag put upon the thread 76 by the spring 117 acting through the discs 110 and 111.

As illustrated in the drawings, and more particularly Figs. 1, 2 and 26 thereof, my novel means for varying the tensional drag on the needle thread in accordance with the requirements encountered in sewing heavy paper bags or the like, has been shown in combination with a thread take-up mechanism set forth and described in the co-pending application of Paul Kuhlig, Ser. No. 646,436, filed December 9, 1932. While my invention is not limited to use in combination with the device set forth and claimed in the aforesaid application of Paul Kuhlig, nevertheless, its advantages and utilities are considerably enhanced, and the operation of the sewing machine as a whole is rendered more advantageous when my device is thus combined with the aforesaid thread take-up mechanism, and, therefore, I now briefly describe the nature and manner of operation of the aforesaid thread take-up mechanism, as well as the manner in which my novel thread-tension relief mechanism cooperates therewith.

Referring now to Figs. 1 and 26, the aforesaid thread take-up mechanism comprises a cam 150 which is mounted on a tubular extension 151 suitably secured to the frame 1 and projected outwardly therefrom. One side of this tubular extension 151 is provided with a slot 152 in which the eye 113 on the reciprocating needle bar 41 travels.

The cam 150 is designed to permit a limited amount of slack in the thread 76 at the start of the forward reciprocation of the needle bar 41 and the needle 40, some slack being necessary for 75

the formation of a loop by the needle. It is also so designed that after the needle bar 41 reciprocates, the cam 150 takes up the slack in the needle thread 76 and permits it to be paid out as required, thereby avoiding breaking of the thread or tearing of the material being sewn. It is also so designed that upon retraction of the needle bar 41, the needle thread 76 is taken up sufficiently to withdraw a portion thereof back through the eye of the needle 40 and to decrease the size of the loop formed by the needle and insure its being properly caught by the descending looper 51. This cam 150 also cooperates with the moving eye 113 in such manner that as the needle bar 41 continues to be retracted the stitch just formed is drawn tight.

To accomplish these purposes, the cam plate 150 may be of various formations, but as shown in Fig. 26 has a substantially circular salient cam portion 153 on the side nearest the needle 40 and a receding cam portion 154 on the side remote from the needle 40.

In the position illustrated in Fig. 1, in which the needle 40 is shown in its fully retracted position, that portion of the needle thread 76 between the tubular guide 112 and the eye 113 is wholly free from the cam 150 and the needle thread 76 does not engage the cam 150 until the needle bar 41 and the eye 113 have moved forward a short distance to the position of Fig. 2. It will therefore be apparent that this free movement of the eye 113 between the point of engagement of the needle thread 76 with the cam 150 and the fully retracted position of the eye 113, upon retraction of the needle 40, provides for paying out the necessary amount of thread for the next ensuing stitch and, on the immediately succeeding forward movement of the needle 40 and the eye 113, for the limited slack in the needle thread 76 which is necessary for the subsequent formation of the loop forming the upper side of the thread triangle which increases in length as the looper travels from the position of Fig. 8 to the position of Fig. 11.

As the needle 40 and the eye 113 move forward, that is to say to the right as viewed in Fig. 1, the needle enters the material and enters the triangle of thread shown in Figs. 9 to 14. During this movement, the length of the needle thread 76 between the eye 113 and the outlet of the tubular guide 112 is caught by the portion 154 of the cam 150 and is deflected outwardly of the cam 150 as in Fig. 2. One of the reasons for the additional tensioning device is now apparent, this reason being that the side of the thread triangle formed by the loop in the needle thread 76 (Fig. 11) must be maintained in a tight condition during the relatively long period of time during which the area of the thread triangle is maintained at its greatest and the needle is entering the triangle. As seen in Fig. 11, this needle thread loop is maintained in position on the face of the then rising looper 51 by the points or slight elevations on the face of the looper. These slight elevations would not be sufficient to hold the loop if the thread were not under greater tension than normal, and as seen in Fig. 27, this portion of the cycle is within the portion C when the full tension is applied. It is thus made certain that the thread triangle will be maintained during the relatively long period of time from its formation to its being stripped from the looper, and conversely that the needle thread loop will be positively stripped from the looper (Figs. 14 and 17), and the machine is thereby prevented from drop-

ping stitches, or from mixing stitches, or from breaking the mechanism or threads.

As the needle 40 moves forward still farther, the length of thread between the end of the tubular guide 112 and the eye 113 passes around the salient portion 153 of the cam 150, and, as the needle reaches its fully projected position, the length of thread between the outward end of the tubular guide 112 and the eye 113 slips around the rounded salient portion 153 of the cam 150 and rides down to the base of the cam adjacent the tubular support 151, the tension devices 110 and 111 being operative up to this point (Fig. 27).

As the needle 40 then starts its return stroke, the cam 150 cooperates with the retracting eye 15 113 to draw upon the loop being formed by the needle in so retracting, and thereby limiting the size of the loop (Fig. 18). This prevents the formation of an excessively large loop by the needle in retracting, which large-size loop, if permitted to be formed in high speed sewing, would be liable to drop down and not be caught by the looper 51, thereby causing the sewing machine to drop a stitch.

As the needle 40 continues to be retracted, the slack in the needle thread 76 continues to be drawn up by the cam 150, thus drawing the just formed stitch tightly against the material being sewn. However, at this time, the cam 123 acts to separate the discs 110 and 111, thereby preventing the combined force exerted by the feed mechanism and the cam 150 from imposing so great a force upon the needle thread 76 as to break the same or to injure the material being sewn.

During the final retracting movement of the needle 40, as set forth hereinabove, the needle thread 76 is drawn free from the cam plate 150 to the starting position illustrated in Fig. 1 thereby paying out additional thread from the source of supply for the formation of the next succeeding stitch.

From the foregoing, it will be apparent that my invention provides improved means for stitching relatively heavy and rigid materials such as multiply paper at high speed. My invention contributes to the accuracy of the stitch formation and to the ease and facility with which a relatively tight stitch may be accomplished without injury to the thread or the material being sewn.

While I have hereinabove described my invention with respect to a preferred embodiment thereof, it will readily be understood by those skilled in the art that my invention is not limited to the details of this embodiment but may variously be utilized and embodied within the scope of the claims hereinafter made.

I claim:

1. In a sewing machine for forming a double-thread interlocked chain stitch, a needle adapted to carry a thread and to be reciprocally moved to pierce the material being sewn with said thread at stitching intervals, a looper mounted for motion both along and about an axis extending parallel to the direction of movement of the material being sewn, said looper being curved radially with respect to said axis, and actuating means for said looper adapted to cause it to move alternately along and about said axis in a closed path in the shape of an oval with a flattened end, the movement across said flattened end being timed to occur as the needle and looper co-operate to form a stitch whereby substantial movement of said looper is avoided as the stitch is being formed.

2. In a sewing machine, means for feeding ma- 75

- material therethrough in a series of intermittent movements, a thread-carrying needle adapted to be reciprocated to pierce said material and be withdrawn therefrom between successive movements of said material, with respect to the sewing machine, thereby forming a thread loop, a looper carrying a second thread and mounted on a pin having a principal axis extending parallel to the plane of the material being sewn, 5
- 10 and means adapted to reciprocate said looper in alternate harmonic movements along and about said axis to cooperate with said needle to form a line of stitching, said means comprising a drive shaft, an eccentric device mounted on said shaft, 15 a connecting rod driven by said eccentric device, and means for translating the longitudinal and lateral reciprocation of said rod produced by said eccentric device to said looper to produce reciprocal motions in one direction and alternate 20 reciprocal motions in a direction normal to said first-mentioned direction comprising a dumbbell link connecting said looper and said connecting rod and mounted to pass through a horizontal plane during the time that the needle approaches 25 the looper whereby substantial movement of said looper is avoided during the time that the stitch is being formed, the resulting motion of said looper defining an oval path with a flattened end.
- 30 3. In a sewing machine, means for feeding material to be sewn through said machine in a series of intermittent movements, a thread-carrying needle adapted to pierce said material and be withdrawn therefrom between successive movements of said material with respect to the sewing machine, and means for controlling the tension of the needle thread as it is paid out by the needle motion, comprising a device adapted to impose a constant frictional drag upon the needle 35 thread, a second device adapted to impose an additional frictional drag upon the needle thread and means actuated in timed relation to the movement of said feeding means and said needle for releasing said thread from the additional 40 frictional drag of said second device during such time as the material being sewn is advancing relative to the sewing machine.
4. In a sewing machine, means for feeding material therethrough in a series of intermittent 50 movements, a thread-carrying needle adapted to be reciprocated to pierce said material and be withdrawn therefrom between successive movements of said material with respect to the sewing machine, a looper carrying a second thread, a 55 holder therefor mounted on a pin having a principal axis extending parallel to the direction of movement of the material being sewn, means adapted to reciprocate said looper in a closed path to cooperate with said needle to form a line of stitching, said means comprising means for reciprocating said looper holder to and fro along said pin, a member adapted to be reciprocated along a line at right angles to the direction of movement of said needle and the principal axis of said pin, and a link pivotally connected at its 60 opposite ends to said looper holder and said reciprocating member, said looper holder reciprocating means and said member being actuated in timed relation to each other to produce a series of alternated movements of said looper holder along said pin and about said pin, respectively.
5. In a sewing machine, means for feeding material therethrough in a series of intermittent 65 movements, a thread-carrying needle adapted to be reciprocated to pierce said material and be withdrawn therefrom between successive movements of said material with respect to the sewing machine, a looper carrying a second thread, a 70 holder therefor mounted on a pin having a principal axis extending parallel to the direction of movement of the material being sewn, means adapted to reciprocate said looper in a closed path to cooperate with said needle to form a line of stitching, said means comprising a main drive shaft rotating in timed relation to said needle, an eccentric mounted thereon, a member connected thereto adapted to reciprocate along a line at right angles to the needle, a rigid 75 link pivotally connected at its opposite ends to said looper holder and said member, respectively, and means operating in timed relation to the rotation of said main drive shaft for reciprocating said looper holder to and fro along said pin.
6. In a sewing machine, means for feeding material therethrough in a series of intermittent 80 movements, a thread-carrying needle adapted to be reciprocated to pierce said material and be withdrawn therefrom between successive movements of said material with respect to the sewing machine, a looper carrying a second thread, a 85 holder therefor mounted on a pin having a principal axis extending parallel to the direction of movement of the material being sewn, means adapted to reciprocate said looper in a closed path to cooperate with said needle to form a line of stitching, said means comprising a main drive shaft rotating in timed relation to said needle, an eccentric mounted thereon, a member con- 90

principal axis extending parallel to the direction of movement of the material being sewn, means adapted to reciprocate said looper in a closed path to cooperate with said needle to form a line of stitching, said means comprising means for reciprocating said looper holder to and fro along said pin, a member adapted to be reciprocated along a line at right angles to the direction of movement of said needle and the principal axis of said pin, and a link pivotally connected at its 100 opposite ends to said looper holder and said reciprocating member, said looper holder reciprocating means and said member being actuated in timed relation to each other.

6. In a sewing machine, means for feeding material therethrough in a series of intermittent movements, a thread-carrying needle adapted to be reciprocated to pierce said material and be withdrawn therefrom between successive movements of said material with respect to the sewing machine, a looper carrying a second thread, a holder therefor mounted on a pin having a principal axis extending parallel to the direction of movement of the material being sewn, means adapted to reciprocate said looper in a closed path to cooperate with said needle to form a line of stitching, said means comprising means for reciprocating said looper holder to and fro along said pin, a member adapted to be reciprocated along a line at right angles to the direction of movement of said needle and the principal axis of said pin, and a link pivotally connected at its opposite ends to said looper holder and said reciprocating member, said looper holder reciprocating means and said member being actuated in timed relation to each other to produce a series of alternated movements of said looper holder along said pin and about said pin, respectively.

7. In a sewing machine, means for feeding material therethrough in a series of intermittent movements, a thread-carrying needle adapted to be reciprocated to pierce said material and be withdrawn therefrom between successive movements of said material with respect to the sewing machine, a looper carrying a second thread, a holder therefor mounted on a pin having a principal axis extending parallel to the direction of movement of the material being sewn, means adapted to reciprocate said looper in a closed path to cooperate with said needle to form a line of stitching, said means comprising a main drive shaft rotating in timed relation to said needle, an eccentric mounted thereon, a member connected thereto adapted to reciprocate along a line at right angles to the needle, a rigid link pivotally connected at its opposite ends to said looper holder and said member, respectively, and means operating in timed relation to the rotation of said main drive shaft for reciprocating said looper holder to and fro along said pin.

8. In a sewing machine, means for feeding material therethrough in a series of intermittent movements, a thread-carrying needle adapted to be reciprocated to pierce said material and be withdrawn therefrom between successive movements of said material with respect to the sewing machine, a looper carrying a second thread, a holder therefor mounted on a pin having a principal axis extending parallel to the direction of movement of the material being sewn, means adapted to reciprocate said looper in a closed path to cooperate with said needle to form a line of stitching, said means comprising a main drive shaft rotating in timed relation to said needle, an eccentric mounted thereon, a member con-

nected thereto adapted to reciprocate along a line a right angles to the needle, a rigid link pivotally connected at its opposite ends to said looper holder and said member, respectively, and a second 5 eccentric device actuated by said main drive shaft adapted to reciprocate said looper holder to and fro along said pin.

9. In a sewing machine, a needle bar having a thread-carrying needle adapted to be alternately advanced into and retracted from the material being sewn, a first tension device for imposing a constant frictional drag upon the needle thread, a second tension device for intermittently imposing additional frictional drag 10 upon the needle thread, means comprising a fixed thread-engaging cam mounted adjacent said needle bar for taking up slack in the needle thread between said devices and said needle as the latter is withdrawn from its fully advanced 15 position to its fully retracted position and vice versa, and means for releasing the additional frictional drag exerted upon said thread by said second tension device during the time that said needle is being retracted from the material being 20 sewn.

10. In a sewing machine, a needle carrying a needle thread, means to thrust said needle through the material being sewn during each 25 cycle of the machine at stitching intervals, a

looper carrying a looper thread and cooperating with said needle to form a stitch at each cycle of the machine, said needle and looper cooperating at the end of one cycle to provide a thread triangle defined on two sides by said looper 5 thread and on the other side by a loop of said needle thread passed around said looper, which thread triangle the needle enters during the next cycle of the machine, a tension device exerting a continual drag upon said needle thread during the entire cycle, and a second tension device exerting further drag on said needle thread 10 during a portion of each cycle, said second tension device operating during the passage of said needle into said thread triangle in order to maintain the side thereof formed by the loop of the needle thread under extra tension and thereby insure maintenance of the area of said thread triangle at a maximum during a substantial portion 15 of a cycle and insure the stripping of said loop from said looper after the needle has fully penetrated said triangle, and said second tension device being rendered inoperative prior to the formation of the succeeding thread triangle 20 in order that a sufficient length of needle thread 25 may be pulled through the needle to form the loop comprising the thread side of the succeeding thread triangle.

HOWLAND F. BRIGGS.
